PHOTOGRAPHIC FLASH EQUIPMENT OF THE BATTERY-CONDENSER TYPE

Friedrich-Wilhelm Scholkemeier, Braunschweig, Germany, assignor to Franke & Heidecke, Fabrik Photographic Präzisions-Apparate, Braunschweig, Germany, a firm

Application December 16, 1953, Serial No. 398,561

Claims priority, application Germany December 17, 1952

11 Claims. (Cl. 67—31)

This invention relates to photographic flash equipment of the kind often referred to as the battery-condenser type, in which a small battery is used to charge an electric condenser or capacitor, and in which the electrical energy stored in the condenser or capacitor is used to ignite or fire the flash bulb. Apparatus of this general type is known, but such apparatus in the previously known forms is not entirely satisfactory, particularly when it is desired to connect one or more additional or supplementary flash bulb sockets to the socket of the main or primary flash bulb.

Among the difficulties likely to arise upon the use of additional or supplementary bulbs in apparatus as heretofore used, may be mentioned the following: If the supplementary bulb is connected in parallel with the main bulb, there is no longer any complete assurance of firing, inasmuch as the discharge current of the condenser is split up among two or more parallel paths. Thus firing failures are likely to result, particularly if different types of flash bulbs are used in different sockets. If one or more additional flash bulbs are connected in parallel to the series connection of the main bulb and its condenser, the additional bulbs form a closed circuit with the condenser and the main flash bulb, so that if the additional bulbs are inserted in their sockets after the main bulb has already been inserted in its socket, all of the bulbs are likely to be fired at the moment of the last connection. On the other hand, if the additional bulbs, with this arrangement, are inserted in their sockets first, and the main bulb is inserted last, then no charging of the condenser will take place, as the charging current will be shunted through the additional bulbs, so that a failure of firing of all the bulbs will result. Or again, if each additional bulb is provided with its own condenser in series with the bulb, and if all of the additional bulbs and their series condensers are connected in parallel to the battery, a failure to fire is also possible. Upon the insertion, at the latest, of the third bulb in its socket, a firing of at least this third bulb is likely to occur since the condensers of the first two bulbs have meanwhile become charged, and will discharge in a pulse-like manner into the newly connected condenser upon insertion of the third bulb.

An object of the present invention, therefore is the provision of generally improved and more satisfactory photographic flashlight apparatus of the battery-condenser type, so designed and constructed as to permit the convenient and reliable use of any desired number (within reason) of additional or supplementary flash bulbs, in combination with the main or primary flash bulb.

Another object is the provision of such apparatus or equipment so designed and constructed that premature firing or failure to fire will not occur, regardless of the order in which the various bulbs are inserted in their sockets or holders.

A further object is the provision of simple photoflash equipment suitable for use with electrolytic condensers, including a switch to interrupt the residual current which tends to flow through condensers of the electrolytic type.

2

A still further object is the provision of a construction in which the switch for interrupting the residual current is built into one of the bulb sockets so as to be automatically operated by insertion or removal of the flash bulb.

5 These and other desirable objects may be attained in the manner disclosed as an illustrative embodiment of the invention in the following description and in the accompanying drawings forming a part hereof, in which:

Fig. 1 is a diagrammatic or schematic view of a construction in accordance with a preferred embodiment of the invention; and

Fig. 2 is a schematic drawing of part of the construction shown in Fig. 1, illustrating additional details.

The same reference numerals throughout the several 15 views indicate the same parts.

Referring first to Fig. 1 of the drawings, there is here shown diagrammatically flash equipment in the form of a main flash unit or flash gun comprising the parts within the dotted rectangle 41, with provision for adding supplementary or additional flash units or flash guns of any desired number, as shown by the parts outside of the rectangle 41. The main unit or primary unit includes, within a suitable casing or frame, a battery 1 (for instance, a battery providing 22.5 volts) connected in circuit with a 20 protective resistance 2 (for instance, a resistance of 2500 ohms), the circuit further extending through a switch 12 to a condenser or capacitor 3 (having a capacitance, for instance, of 100 microfarads), the circuit from the condenser 3 back to the battery 1 having in series a resistance 25 of a value, for example, of 2500 ohms. Arranged in parallel with the resistance 15 is the socket for the main or primary flash bulb 4.

A switch 5 is connected across the main circuit above mentioned, by means of switch wires 30 and 31, the former leading from the switch to the main circuit at a point between the resistance 2 and the switch 12, and the other wire 31 leading from the other side of the switch 5 to the main circuit at a point between the battery 1 and the socket of the main flash lamp 4. This switch 5 is the 30 main control switch or operating switch for firing the flash bulb or bulbs. It is here shown diagrammatically as a simple single pole switch mounted on the main unit 41, although in actual practice this main firing switch 5 is usually the synchronizer switch built into the photographic shutter on the camera with which the flash equipment is used, or is a switch forming part of a separate synchronizer attached to and operating with the shutter of such camera, as well understood in the art.

With this arrangement, if the switch 12 is closed, the 35 condenser or capacitor 3 becomes charged from the battery 1, through the resistances 2 and 15, if no bulb is present in the socket of the bulb 4. However, if a bulb is present, the condenser becomes charged through the bulb, which is in parallel with the resistance 15 and which, 40 when present, serves to short circuit the resistance 15, since the resistance 15 has a value considerably higher than the internal resistance of the bulb 4. Preferably the switch 12 is closed automatically by insertion of the bulb 4 into its socket, and is opened automatically by removal 45 or ejection of the bulb from its socket, in the manner disclosed below.

With the condenser 3 fully charged, the closing of the switch 5 will allow the charge in the condenser 3 to flow through the bulb 4, thus firing the bulb in the 50 desired manner. As soon as the bulb is fired and the switch 5 is again opened, the condenser 3 is immediately recharged if the switch 12 remains closed. But upon opening the switch 12, by ejection or removal of the bulb from its socket, the circuit from the battery to the condenser is broken and thus there is no wastage of current from the battery while there is no lamp in the socket, which wastage would otherwise occur if the switch 12

were not present, on account of the residual current characteristics of the condenser 3 if this condenser is of the electrolytic type.

For enabling connection of any desired number of additional or supplementary flash units, the terminals 8 and 9 are provided, of any suitable form such as male and female plug terminals or bayonet joint terminals. The terminal 8 is connected to the switch side of the condenser 3 while the terminal 9 is connected to the battery side of the bulb 4 and resistance 15. Each supplementary unit comprises a flash bulb socket and a condenser in series with each other, to be connected across the terminals 8 and 9, and a resistance in parallel around the bulb socket, the resistance being of greater resistance than that of the flash bulb, just as in the case of the resistance 15 which is of greater resistance than the bulb 4. Thus, for example, the lamp 6 and condenser 10 of one supplementary unit are connected across the terminals 8 and 9, in series with each other, and with a resistance 16 in parallel around the socket of the lamp 6. If a second supplementary unit is to be used, the socket of its lamp 7 is connected in series with the condenser 11, likewise across the terminals 8 and 9 and in parallel with the lamp 6 and condenser 10, and a supplementary resistance 17 is connected in parallel around the lamp 7, as shown in Fig. 1. Any desired number (within reason) of additional supplementary units may be added in the same way.

If the supplementary unit or units are connected across the terminals 8 and 9 of the main unit of flash gun 41, in the manner shown, it is seen that all of the condensers 3, 10, and 11 will be charged by the battery 1, as soon as the switch 12 is closed (or as soon as the supplementary units are connected to the main unit, if the switch 12 is already closed) regardless of whether there are bulbs in the various sockets and regardless of the order in which bulbs or fresh bulbs are inserted in the various sockets, for in each case the condensers 3, 10, and 11 are charged through their respective resistances 15, 16, and 17, if no bulbs or if burned out bulbs are present. Thus the order or sequence in which bulbs are inserted is immaterial, due to the provision of the resistances, and the electric equilibrium is not disturbed by the insertion of new bulbs.

As already mentioned, the switch 12 is preferably operated automatically by insertion of the bulb 4 in its socket, or removal of the bulb from the socket. This is shown diagrammatically in Fig. 1, and in somewhat greater structural detail in Fig. 2. The base contact 14 of the bulb socket is formed on a leaf spring which also carries the insulating plate 24 on which one side 12 of the switch is carried. The axial insertion of the shank 20 of the bulb 4 into its socket 21 causes the central contact 23 of the bulb to press on the central contact member 22 of the socket (the member 22 being formed on the spring 14) and thereby flexes the spring 14, carrying the insulating plate 24 and the switch part 12 in a downward direction when viewed as in Fig. 2, until the switch part 12 comes into contact with a spring arm 25 constituting the other side of this switch. Thus the switch is closed upon insertion of the bulb 4, and it springs open again when the bulb 4 is removed or ejected. The bulb, as customary, is held in the socket by means of a bayonet slot in the side walls of the socket engaging radial pins or projections on the shank of the bulb, although a screw type of bulb shank and socket could be used if desired.

The contact member 25 constituting the other side of the switch 12 is in the form of a wiper arm constantly pressing against and in conductive relation to the conducting disk 26 formed on one side of the cable drum or cord drum 27 which is rotatively supported on the housing 28 of the flash gun or flash unit. On the drum 27 is reeled the two wire electric cable or cord 29 containing the wires 30 and 31 which lead, as above men-

tioned, to the main firing switch 5 which is located on the associated photographic camera or its shutter. The wire 30 is electrically connected to the disk 26 so that it is conductively connected to the spring 25, while the other wire 31 of the cable 29 is electrically connected to the metal disk 32 which makes connection with the lamp housing 28, thus being grounded on the housing of the flash unit, which constitutes one side of the electric circuit. A hand wheel or knob 43, mounted on the shaft of the reel 27 and accessible externally of the casting 28, serves for manually turning the reel 27 to wind up the core 29 when the flash gun or unit is disconnected from the camera.

In the preferred arrangement, as above set forth, there is a protective resistance 15, 16, 17 connected in parallel around each of the flash bulbs 4, 6, and 7, respectively. This is preferred because with this arrangement it is immaterial in which order or sequence the various bulbs are renewed, after firing. But if the operator takes care to insert the fresh bulbs in the supplementary flash guns first, and then to insert a fresh bulb 4 in the main flash gun after the supplementary gun bulbs have been replenished, the supplementary units can be used safely in connection with an old style flash unit which does not have the protective resistance 15. With such an arrangement, the condensers 10 and 11 of the supplementary units will be charged before the bulb 4 of the main unit is renewed, and then when the main bulb is renewed it will not be prematurely fired. Hence the supplementary units of the present invention have the double advantage that they can be successfully employed also with a main unit or flash gun of the standard type in accordance with the prior art, but the greatest advantages of the present invention are achieved, of course, when the supplementary units in accordance with the present invention are employed with a main unit which is also of the new kind in accordance with the present invention.

Since it has been mentioned above that a fired flash bulb is replaced by a fresh bulb, it will be apparent to those skilled in the art that the flash bulbs in question are of the ordinary photoflash type, having a glass envelope filled with shredded foil or wire made of magnesium or other combustible material. Thus these photoflash bulbs may be referred to as bulbs of the combustible and consumable type, usable only once, as distinguished from the gas filled multiple flash type of bulb which may be flashed repeatedly and is not limited to a single flash operation. The problems to be solved in dealing with bulbs of the consumable type are different from those encountered in gas filled bulbs of the repetitive type, for the latter will conduct no current until a certain critical voltage is reached, whereas the ordinary photoflash bulbs of the consumable type have a relatively low internal resistance and will conduct some current at any voltage. It is this fact which accounts for certain types of misfiring or malfunctioning of photoflash apparatus when using consumable bulbs, and which accounts for the fact that various electric circuit arrangements which are suitable for use with gas filled repetitive flash bulbs are not suitable for use with photoflash bulbs of the ordinary combustible or consumable type.

It is seen from the foregoing disclosure that the above mentioned objects of the invention are well fulfilled. It is to be understood that the foregoing disclosure is given by way of illustrative example only, rather than by way of limitation, and that without departing from the invention, the details may be varied within the scope of the appended claims.

It will be seen from Fig. 2 that the photoflash bulb 4, when inserted into its socket, makes full contact with its feed contacts 21, 22 before the members 14, 24 are displaced far enough to close the switch 12.

The values of the condensers or capacitors in the supplementary flash unit or units, and of the resistances or

resistors therein, are preferably substantially the same as those in the main unit. Thus the capacitors 3, 10, and 11 preferably all have a capacity of about 100 microfarads, or in the order of magnitude of about 100 to 200 mf. The resistors 15, 16, and 17 preferably all have resistances of about 2500 ohms, these resistances being substantially higher than the internal resistances of the photoflash bulbs 4, 6, and 7.

What is claimed is:

1. A supplementary photographic flash unit for electrical connection in parallel with a photoflash bulb and condenser of a main flash unit of the battery-condenser type, said supplementary unit comprising a supplementary socket for holding a supplementary photoflash bulb, a supplementary condenser electrically connected in series with said socket, a protective resistor electrically connected in parallel with said socket and in series with said supplementary condenser, said resistor having a resistance substantially larger than that of a photoflash bulb intended to be used in said supplementary socket, and electrical leads for connecting one side of said supplementary condenser and the remote sides of said supplementary socket and resistor to a main flash unit.

2. A photographic flash unit comprising an electric circuit including a battery, a condenser, and a photoflash bulb socket all in series with each other, a protective resistor arranged in said circuit in parallel with said bulb socket and in series with said battery and condenser, the resistance of said resistor being greater than the resistance of the photoflash bulb used in said socket, and an electric switch operatively interposed in said circuit between said battery and said condenser.

3. A photographic flash unit comprising an electric circuit including a battery, a condenser, and a photoflash bulb socket all in series with each other, a photoflash bulb of the consumable non-repetitive type operatively connected in said socket, a protective resistor arranged in said circuit in parallel with said bulb socket and in series with said battery and condenser, the resistance of said resistor being greater than the resistance of the photoflash bulb used in said socket, a bulb firing circuit operatively connecting the respectively remote sides of said condenser and said socket to each other independently of said battery, and a firing switch in said firing circuit to open and close the same.

4. A construction as defined in claim 3, in which said firing switch is mounted on a photographic camera and in which said photoflash bulb is so placed as to illuminate the scene to be photographed by the camera, and in which said firing circuit includes a flexible cord extending from said flash unit to the camera on which said switch is mounted, said unit further including a built-in reel on which said cord may be wound when not in use, and an externally accessible handle for turning said reel to wind said cord thereon.

5. A photographic flash unit comprising an electric circuit including a battery, a condenser, and a photoflash bulb socket all in series with each other, a protective resistor arranged in said circuit in parallel with said bulb socket and in series with said battery and condenser, the resistance of said resistor being greater than the resistance of the photoflash bulb used in said socket, and a supplementary flash unit for electrical connection to said first mentioned unit for firing simultaneously therewith, said supplementary unit including a supplementary socket for holding a supplementary photoflash bulb, a supplementary condenser electrically connected in series with said supplementary socket, a supplementary resistor electrically connected in parallel with said supplementary socket and in series with said supplementary condenser, said supplementary resistor having a resistance greater than the resistance of the photoflash bulb used in said supplementary socket, and circuit connections for electrically connecting the respectively remote sides of said supplementary condenser and supplementary socket re-

spectively to the corresponding sides of said condenser and socket of said first mentioned unit.

6. A construction as defined in claim 2, further including means for automatically closing said switch upon insertion of a photoflash bulb into said socket and opening said switch upon removal of a bulb from said socket.

7. A construction as defined in claim 6, in which said bulb socket includes two feed contact members for making electrical contact with a photoflash bulb inserted into said socket, and in which said means closes said switch only after a bulb, during insertion in said socket, has made contact with both of said feed contact members.

8. A supplementary photographic flash unit for electrical connection in parallel with a main photoflash bulb of the combustible and consumable type and with a condenser of a main flash unit of the battery-condenser type, said supplementary unit comprising a supplementary bulb socket, a supplementary photoflash bulb of the combustible and consumable type electrically connected in said socket, a supplementary condenser electrically connected in series with said socket and with said supplementary bulb therein, a protective resistor electrically connected in parallel with said socket and supplementary bulb and in series with said supplementary condenser, said resistor having a resistance substantially larger than that of said supplementary bulb, and electrical leads for connecting the side of said supplementary condenser which is remote from said supplementary bulb and the sides of said supplementary socket and resistor which are remote from said supplementary condenser to a main flash unit.

9. The combination with a main photoflash unit comprising a source of current, a first resistor and a main photoflash bulb electrically connected in series with each other and with said source, a second resistor electrically connected in parallel with said photoflash bulb and in series with said first resistor and said source, and a main condenser electrically connected in series with said source, first resistor, and second resistor, of a supplementary photoflash unit comprising a supplementary condenser and a supplementary photoflash bulb electrically connected in series with each other and in parallel with said main condenser and main photoflash bulb, and a supplementary resistor electrically connected in parallel with said supplementary bulb in bypass relation thereto, said supplementary photoflash unit having no separate source of current of its own.

10. The combination with a main photoflash unit comprising a source of current, a first resistor and a main photoflash bulb electrically connected in series with each other and with said source, a second resistor electrically connected in parallel with said photoflash bulb and in series with said first resistor and said source, and a main condenser electrically connected in series with said source, first resistor, and second resistor, of a supplementary photoflash unit comprising a supplementary condenser and a supplementary photoflash bulb electrically connected in series with each other and in parallel with said main condenser and main photoflash bulb, and a supplementary resistor electrically connected in parallel with said supplementary bulb in bypass relation thereto, said supplementary photoflash unit having no separate source of current of its own, said photoflash bulbs being of the combustible and consumable type, and all of said condensers being of the electrolytic type.

11. A construction as defined in claim 10, further including an electric switch in the series connection between said source of current and said main condenser, a bulb socket for said main photoflash bulb, and means operated by insertion of said main bulb in said socket for closing said switch and operated by removal of said main bulb from said socket for opening said switch.
